Primary Examiner — Cynthia Ramirez*Assistant Examiner* — Gino Colan(74) *Attorney, Agent, or Firm* — AJ D. Martinez; Latham, Wagner, Steele & Lehman, P.C.(57) **CLAIM**

The ornamental design for a directional control valve locking device, as shown and described.

DESCRIPTION

FIG. 1 is an exploded isometric view of a directional control valve locking device showing our new design;

FIG. 2 is an isometric view thereof; and,

FIG. 3 is another isometric view thereof.

The broken lines shown in the figures are for the purpose of illustrating environment and form no part of the claimed design.

The features of the directional control valve locking device as shown and described in the drawings.
